DESIGN FOR A SHOE

Sebastiano Carrabba, Brooklyn, N. Y., assignor to Dainty Maid Slippers, Inc., Brooklyn, N. Y.

Application November 21, 1936, Serial No. 66,071

Term of patent 3½ years

To all whom it may concern:

Be it known that I, Sebastiano Carrabba, a citizen of the United States of America, residing in the Borough of Brooklyn, county of Kings, city and State of New York, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view of a shoe as shown in Fig. 1.

I claim:

The ornamental design for a shoe substantially as shown.

SEBASTIANO CARRABBA.
